UNITED STATES PATENT OFFICE.

GOTTFRIED GAERTNER, OF NEWARK, NEW JERSEY.

FLY-PAPER HOLDER.

1,109,571.

Specification of Letters Patent.

Patented Sept. 1, 1914.

Application filed March 21, 1914. Serial No. 826,329.

To all whom it may concern:

Be it known that I, GOTTFRIED GAERTNER, a citizen of the United States, residing at Newark, in the county of Essex and State of New Jersey, have invented certain new and useful Improvements in Fly-Paper Holders, of which the following is a specification.

This invention relates to fly paper holders in which one of the objects is to provide a supporting base the opposite sides of which are adapted for detachable engagement with the fly paper holder thereby especially adapting the same for association with ceilings or the like, wherein a double contacting face 15 against which the flies abut will be provided.

Another object of the invention is to provide improved clamping means which detachably engage the fly paper with the supporting base and at the same time, prevent the contacting thereof upon which it is carried should it be desired to lay the same upon a table or the like, and at the same time, providing ample space therebeneath, so as to allow for the entrance of flies, permitting them to contact with the fly paper of the underside as well as the upper side of the supporting base when the device is laid on a table as above pointed out, the clamping elements being so constructed as to be 25 expediently disengaged from the fly paper by the operator when so desired.

A further object of the invention is to provide clamping elements so constructed as to clamp the paper on both sides of the supporting base and to provide finger-loops by which the clamps are readily disengaged from the paper, and at the same time, providing spacing members in order to hold the fly paper in spaced relation to the objects 40 with which they are engaged.

Other objects as well as the nature, characteristic features and scope of my invention will be more readily understood from the following description taken in connection with the accompanying drawings and pointed out in the claims forming a part of this specification.

Referring to the drawings: Figure 1 is a plan view of the device constructed in accordance with my invention illustrating the application thereof, Fig. 2 is a side elevation of the same, showing fly paper detached from one side thereof, and Fig. 3 is an end view of the same.

In the drawings, wherein is illustrated the

preferred embodiment of this invention a base or support 5 is provided which in the present instance comprises an ordinary plate of wood, metal or any other suitable material in which is mounted a hook 6 by which the device is pendently supported on the ceiling, wall or any other suitable place. The fly paper as indicated on the drawings at 7, is engaged with the opposite sides of the supporting base 5, the said base being 65 of such a size as to accommodate standard sizes of fly paper.

The means by which the fly paper 7 is secured to the opposite sides of the base 5 in the present instance comprises a plurality 70 of identical clamping elements 8, each of which is formed from a single metallic resilient strap, the opposite ends of which are bent to provide loop eyes 9 which engage with the paper on the opposite sides of the 75 base 5, while the ends adjacent the loop eyes 9 are turned at right angles to the body in order to provide a substantially U-shaped structure in side elevation, the vertex 10 of the U being engaged with the opposite end of the base 5, as shown to advantage in Figs. 1 and 2. By this peculiar formation of clamps it is obvious that the paper is yieldingly engaged with the supporting base at both ends thereof, the looped ends 9 not only 80 providing clamping means in order to hold the paper to the base, but likewise being of a sufficiently large size to accommodate a finger therein in order that the paper may be readily disengaged from the base when 85 so desired, the loops 9 likewise serving the purpose of spacing elements in order to prevent the contact of the paper 7 with a table or other object upon which the device is laid, it being of course understood that the 90 holder may be supported in this manner as well as by the hook 6.

In operation we will assume that the clamping elements 8 are engaged with the opposite ends of the base 5 in the manner shown in the drawings. The fly paper is then engaged beneath the loop side 9 of the clamp, on the opposite sides of the base 5, the sticky face of the paper being on the outer side in order that flies in contact therewith will be held. If desired, a quantity of sheets may be laid on each side of the base 5 in view of the resilient character of the clamping element 8, the latter allowing for the expansion of the loop eyes 9 to a 105

considerable extent in order to accommodate a plurality of pieces of paper therebeneath, if so desired.

It will be understood that the above description and accompanying drawings comprehend only the general and preferred embodiment of my invention and that various minor changes in details of construction, proportion and arrangement of parts may be made within the scope of the appended claims and without sacrificing any of the advantages of my invention.

Having thus fully described my invention what I claim as new and desire to secure by Letters Patent is:

1. A fly paper holder including a base the opposite sides of which are adapted for engagement with the paper, and means carried by the base and having a portion engaged with each face of the latter for clamping the paper on both sides of the base.

2. A fly paper holder including a base, the opposite sides of which are adapted for engagement with the fly paper, and means arranged on opposite ends of the base and engaging with the opposite sides thereof to hold the paper thereon.

3. A fly paper holder including a base, the opposite sides of which are adapted for engagement with the fly paper, straps arranged on the base, the end of each strap engaging the opposite side of said base to hold the fly paper thereon.

4. A fly paper holder including a base, the

opposite sides of which are adapted for engagement with the fly paper, a plurality of elements for clamping the paper in engagement with the base, each of said elements comprising a metallic resilient strap, the opposite ends of which are looped for resilient engagement with the paper on the opposite side of the base, said loops accommodating the fingers of the operator therein in order to disengage the same from the paper and likewise providing spacing elements so as to hold the fly paper in spaced relation to the object with which it is engaged.

5. A fly paper holder including a base the opposite sides of which are adapted for engagement with the fly paper, clamping elements for holding the paper against the opposite sides of the base, each of which comprises a metallic resilient strap the opposite ends of which are looped for resilient engagement with the paper on the opposite sides of the base, the opposite ends of said strap adjacent said loop being turned at right angles to the body in order to provide a substantially U-shaped element the vertex of which is engaged with the end of the supporting base for the purpose specified.

In testimony whereof I affix my signature in presence of two witnesses.

GOTTFRIED GAERTNER.
